UNITED STATES PATENT OFFICE.

JOSEPH HARRINGTON, OF RIVERSIDE, ILLINOIS.

FEEDING DEVICE FOR FURNACES.

1,075,352.

Specification of Letters Patent. Patented Oct. 14, 1913.

Application filed March 7, 1912. Serial No. 682,159.

To all whom it may concern:

Be it known that I, JOSEPH HARRINGTON, a citizen of the United States, and a resident of Riverside, in the county of Cook and State of Illinois, have invented certain new and useful Improvements in Feeding Devices for Furnaces; and I do hereby declare that the following is a full, clear, and exact description thereof, reference being had to the accompanying drawings, and to the letters of reference marked thereon, which form a part of this specification.

This invention relates to improvements in automatic feeding devices for steam boiler or other furnaces, and more especially to improvements in the mechanism, embracing a horizontally reciprocating pusher, used in connection with the feed hopper of such a feeding device, for advancing the coal from the bottom of the hopper toward and through the feed opening of the furnace.

The invention consists of the matters hereinafter described and more particularly pointed out in the appended claims.

As shown in the drawings: Figure 1 is a view in central vertical section of the lower part of the feed hopper of the furnace, the parts forming the feed opening of the furnace and the pusher mechanism. Fig. 2 is a like vertical section taken upon line 2—2 of Fig. 4. Fig. 3 is a like section taken upon line 3—3 of Fig. 4. Fig. 4 is a view in front elevation of the lower part of the feed hopper and the pusher mechanism associated therewith. Fig. 5 is a horizontal section taken upon line 5—5 of Fig. 1, showing the reciprocating pusher in plan view. Fig. 6 is a detail section taken upon line 6—6 of Fig. 1. Fig. 7 is a detail view of one of the pusher sections as seen from beneath. Fig. 8 is a detail view from beneath, of one end of the beam member of the pusher. Fig. 9 is a detail plan view of one of the brackets which support the beam member of the pusher.

As shown in said drawings, 5, 5, indicate the vertical side or frame plates located at the front of the furnace, which form the end walls of the feed hopper and support the parts constituting the feed opening of the furnace and the pusher actuating mechanism.

6 indicates the front, inclined wall of the feed hopper which extends between the side plates 5, 5.

7 indicates an L-shaped, horizontal, trans-

verse member also extending between said plates 5, 5, and forming the rear wall of the feed hopper and the top wall of the feed opening or throat of the furnace.

60

8 indicates a horizontal fixed beam, extending between the side plates 5, 5 below the level of the feed opening of the furnace and to which is attached a series of cast metal sections 9, 9, 9, which together constitute the horizontal bottom wall of the feed opening or feed plate, over which the fuel is moved in passing from the bottom of the hopper into the furnace.

65

10 indicates a transverse shaft, supported at its ends in the side plates 5, 5, to which is attached a series of inclined plates 11, which together form an inclined surface over which the fuel moves or slides when delivered from the inner edge of the feed plate formed by the sections 9, 9, 9.

70

12 indicates a transversely arranged, horizontal beam extending between side walls 5, 5, forward of the lower edge of the front wall 6 of the hopper. Said beam forms a part or member of the pusher, and, in the operation of the pusher, has backward and forward, horizontal, reciprocatory movement.

75

13, 13, 13 indicate a plurality of intermediate pusher sections and 14, 14, two end pusher sections, which, together with the beam 12 constitute the pusher as a whole. Said pusher sections 13 and 14 are arranged side by side along the beam 12, and are provided with horizontal top surfaces that bear against, or have sliding contact with, the lower edge of the said front wall 6 of the hopper, and with upright inner or forward surfaces which act on the fuel to advance the same into the feed opening. The forward parts of said sections rest and slide upon the horizontal feed plate formed by the sections 9, 9, 9.

80

13, 13, 13 indicate a plurality of intermediate pusher sections and 14, 14, two end pusher sections, which, together with the beam 12 constitute the pusher as a whole. Said pusher sections 13 and 14 are arranged side by side along the beam 12, and are provided with horizontal top surfaces that bear against, or have sliding contact with, the lower edge of the said front wall 6 of the hopper, and with upright inner or forward surfaces which act on the fuel to advance the same into the feed opening. The forward parts of said sections rest and slide upon the horizontal feed plate formed by the sections 9, 9, 9.

85

The beam 12 is given horizontal, reciprocatory movement through suitable actuating devices connected preferably with the ends of said beam, and the several intermediate pusher sections 13, 13, 13 are connected with said beam by means affording lost motion between the beam and said pusher sections and also affording adjustment of the extent of such lost motion separately in the case of each of said sections. The end pusher sections 14, 14, are shown as being attached to the ends of the beam 12, in fixed relation thereto. Now referring to the de-

100

105

110

tails of construction illustrated in these parts, said beam 12 is shown as consisting of a channel-beam having a horizontal web at its top and depending stiffening flanges at its front and rear edges. The said beam 12 is also shown as being stiffened or strengthened against vertical strains by a stiffening girder 15 secured to the central part of its web and depending therefrom. 5

10 The end pusher sections 14, 14, as clearly seen in Fig. 1, are provided with recesses or seats in their under surfaces, to receive the ends of the beam, which latter is held or clamped to the end sections by means of set-screws 16. Secured to each end of the said beam 12 is a horizontally arranged track-plate 17, provided with two parallel downwardly facing bearing surfaces or tracks 18, 18 arranged parallel with and inside of the 15 vertical plate 5, as clearly seen in the detail view, Fig. 8 and in the sectional view Fig. 6. To the inner face of said plate 5 below the end of the beam 12 is secured a bracket 19 provided at its top with two horizontal 20 upwardly facing bearing surfaces or tracks 20, 20, (Fig. 9). Between the upwardly facing surfaces of the tracks 20, 20, and the downwardly facing surfaces of the tracks 18, 18, is located a bearing roller 22. The 25 said bearing roller has two cylindric bearing surfaces, one at each side of its peripheral surface, adapted severally for bearing contact with the tracks 18 and 20. Between said cylindric bearing surfaces, said roller is provided with a series of gear teeth 23, 30 intermeshing with similarly arranged gear teeth 24 and 25 on the track plate 17 and the bracket 19. By the construction described in the supporting means for the 35 ends of the beams 12, the weight of said beam is supported by the bearing rollers, so that it may be moved forward and backward with a minimum of frictional resistance to such movement, while the said rollers are retained in place by the engagement 40 of the gear teeth thereon with those on the plate 17 and bracket 19.

50 In the inner face of each vertical side plate 5, adjacent to the outer end of the track-plate 17, is formed a horizontal guide groove 27 (Fig. 6) and on the said outer end of the track-plate is formed an outwardly extending horizontal guide-flange 28, which enters and slides in said groove 55 27. Said guide-flange fits loosely in the guide groove so that the weight of the beam 12 may rest upon and be carried solely by the roller 22; the said groove and guide-flange serving to hold the beam from tipping or tilting out of its horizontal position. 60

65 The means illustrated for actuating the pusher consists of a horizontal rock-shaft 30 extending across the front of the furnace and having bearings in brackets 31 on the walls 5, 5, together with upwardly ex-

tending crank-arms 32, 32, rigidly secured to said rock-shaft, and links 33, 33, connecting the upper ends of said arms with the end pusher sections 14, 14. As shown, said end pusher sections are provided with integral, outwardly extending lugs 34, 34, between which the inner ends of the links 33 are inserted and with which they are connected by pivot pins 35, 35. 70

Now referring to the details of construction in the several pusher-sections 13, 13, each of said sections (Figs. 2 and 7) is made as follows: Each pusher-section is recessed on its under surface to receive the beam 12 and has the form of a horizontal top wall 80 provided with front or inner and rear or outer depending flanges; the front flange forming the vertical face of the section which acts on the coal in the feeding operation, and having sliding contact at its bottom edge with the feed plate. Said top wall is provided on its outer or rear part with two depending, horizontal projections or flanges having downwardly facing bearing surfaces 38, 38 (Fig. 7) adapted for sliding contact 85 with the top surface of the beam 12. At the outer ends of said bearing surfaces 38, 38, the pusher-section is provided with two upright ribs 39, 39, forming stops for contact with the outer edge of the beam 12 and 90 against which said beam acts in its outward movement to retract or draw rearwardly the pusher-section. Mounted at its ends in the front and rear walls or flanges of the pusher-section is a horizontal screw-shaft 40 which 95 projects through the rear or outer wall of the section and is provided with a squared end to which a wrench may be applied for rotating the screw-shaft. Said screw-shaft is located above the top of the beam 12, and 100 passes through and has screw-threaded engagement with a block 41, which has sliding engagement with an adjacent surface of the section, in such manner that the block is held 105 from rotation, but is adapted to be shifted or adjusted on the section in a direction toward or from the ribs or stops 39, 39. As shown, the block 41 has a flat top surface in 110 sliding contact with the downwardly facing horizontal surface of the top wall of the section above the same, and the lower part of the block projects downwardly below the screw-shaft in position for engagement with the inner face of the beam 12. A collar 42, secured to the shaft 41 adjacent to the inner 115 wall of the section, serves as a shoulder to take the end thrust of the said shaft, and a pin 43, inserted through said shaft adjacent to the outer wall of the section, acts to hold the shaft from outward endwise movement. Said block 41 constitutes an adjustable stop 120 against which the beam 12 acts in its inward movement to give the inward feeding stroke to the pusher-section. Said block 41 will be 125 spaced at such distance from the stops 39, 130

39, as to give the desired degree of lost motion between the pusher section and the beam. By turning the shaft 40, said block 5 may be shifted or adjusted to give any degree of lost motion, that may be found desirable, between the beam 12 and the pusher-section.

As clearly seen in Figs. 6 and 7, the adjacent or meeting margins of the horizontal 10 top walls of the pusher-section are provided with overlapping horizontal flanges 44, 44'. At the side margins of their upright inner walls of each pusher-section, the latter is provided with vertical, outwardly extending 15 flanges 45, 45 (Figs. 2 and 7) adapted for sliding contact with the like flanges on the adjacent pusher-sections so as to form a close joint or connection between the inner end of each pusher-section and that on either side 20 of the same, in all positions of the pusher-sections relatively to the beam 12.

The advantages gained from the general features of construction above described, will be understood from the following: In 25 the operation of furnaces having automatic stoking mechanism, it is necessary for the best or most successful operation of the same that the fuel should be fed into or delivered through the feed opening of the furnace in a layer which is of uniform thickness from side to side of the furnace. It is found in practice that the use of feed devices having a hopper and a reciprocating pusher, as heretofore made, especially where the furnace is of considerable or great width, that the delivery of the coal from the hopper to the feed opening will not be effected uniformly throughout the length of the pusher, but that a greater quantity of coal may be 30 fed forward at each advance movement of the pusher in one part of the length of the latter than in another part, and this difference in the quantity of the different parts of the fuel layer entering over the feed plate. 35 Such variation in the feed of the fuel arises principally from differences in the character of the coal used, and the freedom with which it will flow or descend through and from the hopper. As, for instance, coal consisting 40 of lumps of uniform size will be fed more uniformly than that which contains considerable slack and lumps of varying sizes. In the use of the pusher mechanism made as described, if it be found that the fuel is 45 being fed irregularly as, for instance, in a larger quantity at the middle part of the pusher and in a smaller quantity at the ends of the same, one or more of the pusher sections, at the place where the feed is too 50 great, will be so adjusted so that the front or pushing face of such sections will fall behind the end ones, as the pusher is advanced, with the result that a smaller quantity of fuel will be pushed forward by the 55 retracted pusher section or sections and a

correspondingly smaller quantity of coal will be advanced by the action of such section or sections, in the forward stroke of the pusher. It will be understood that as all of the pusher sections will be fully retracted 70 at the end of such backward movement of the actuating beam, so that their front or pushing faces will stand in line with each other at that time, a uniform maximum opening will be afforded for the dropping 75 of the coal in front of the pusher, throughout the entire length of the same.

An adjustment of the pusher sections, such as is above referred to, is shown in Fig. 5, wherein the sections are shown in 80 the position occupied by them when the pusher is making its advance stroke; and the parts are so adjusted as to give a maximum degree of lost motion in the pusher sections at the middle part of the pusher and a gradually lessening degree of such lost motion from the center toward the ends of the pusher; as required when it is desired to give generally a lessened feed at 85 the center as compared with the ends of the pusher. Manifestly, by adjusting the degree of lost motion between any one of the pusher-sections and the beam, or by variably adjusting the amount of lost motion between several of the pusher-sections and the beam, 90 the feed of the fuel may be controlled at different parts of the length of the pusher, so as to give exactly the amount of feed required at different parts of the feed operating, in order to maintain a uniform thickness in the layer of the fuel delivered to the 95 furnace.

The construction described in the roller-support for the ends of the pusher beam affords important advantages, for the reason that said beam is subject to a considerable load, due to the weight of the pusher-sections and of the coal in the hopper, and the said roller-supports enable the pusher-beam to be easily and smoothly moved or reciprocated, notwithstanding the weight carried by said beam.

The particular form of my invention shown in the accompanying drawings is one which I have found well adapted for practical use but the same may be variously modified its its details without departure from the spirit of my invention, and I do not, therefore, desire to be limited to the special features of construction and details 110 illustrated except so far as the same may be pointed out in the appended claims as parts of my invention.

I claim as my invention—

1. In a furnace, the combination of a reciprocating beam, a plurality of pusher sections arranged in laterally abutting relation along 125 said beam and provided with a front flange and a rear stop, each of said sections embracing said beam between the said front 130

flange and rear stop and having sliding contact therewith, and means associated with each of said pusher sections, adapted to afford a variable degree of lost motion between the section and the beam during the forward movement of the latter.

2. In a furnace, the combination of a reciprocating beam, a plurality of pusher sections arranged in laterally abutting relation along said beam, each of said sections embracing a horizontal top wall having a downwardly facing bearing surface in contact with said beam, a vertical front flange and a stop adapted to engage the rear margin of the beam, and means associated with each of said pusher sections adapted to afford a variable degree of lost motion between the section and the beam during the forward movement of the latter.

3. In a furnace, the combination with a feed plate, of a reciprocating beam located adjacent to said feed plate within the furnace, a plurality of pusher sections arranged in laterally abutting relation along said beam and supported in sliding engagement upon said beam, each of said sections embracing a horizontal top wall, having a downwardly facing bearing surface in contact with said beam, a vertical front flange in sliding contact with said feed plate and a stop adapted to engage the rear margin of the beam, and adjustable means associated with each of said pusher sections adapted to afford a variable degree of lost motion between the sections and the beam during the forward movement of the latter.

4. In a furnace, the combination of a reciprocating beam, a plurality of pusher sections arranged in laterally abutting relation along said beam, each of said pusher sections embracing a horizontal top wall, a vertical front flange, a stop adapted to engage the rear margin of the beam, and longitudinal ribs extending downwardly from said top wall, adapted to have sliding engagement with said beam, and adjustable means adapted to afford lost motion between the section and the beam during the forward movement of said beam.

5. In a furnace, the combination of a reciprocating beam, a plurality of pusher sections arranged in laterally abutting relation along said beam, each of said sections being provided with a downwardly depending front flange and a rear stop, ribs extending longitudinally between said front flange and rear stop and in sliding engagement with said beam, and means associated with each of said sections adapted to afford a variable degree of lost motion between the section and the beam during the forward movement of said beam.

6. In a furnace, the combination with a feed plate, of a reciprocating beam, a plurality of pusher sections arranged in lat-

erally abutting relation along said beam, each of said sections embracing a longitudinal top wall, having a downwardly facing bearing surface in sliding contact with said beam, a vertical front flange having sliding engagement with said feed plate, and a stop adapted to engage the rear margin of said beam, a shaft extending longitudinally of each of said sections beneath its top wall, an adjustable stop mounted on said shaft and having screw-threaded engagement therewith, said stop being adapted for contact with said beam during its forward movement to afford a variable degree of lost motion between said section and said beam.

7. In a furnace, the combination of a reciprocating beam, a plurality of pusher sections arranged in laterally abutting relation along said beam, each of said sections embracing a longitudinal top wall having a downwardly facing bearing surface in contact with said beam, a vertical front flange and a stop adapted to engage the rear margin of the beam, a rotative shaft having bearing in said front flange, a non-rotatable stop mounted upon said shaft and having screw-threaded engagement therewith, said stop being adapted to afford a variable degree of lost motion between the section and the beam during the forward movement of the latter.

8. In a furnace, the combination with a feed plate, of a reciprocating beam, a plurality of pusher sections arranged in abutting relation along said beam, each of said sections comprising a horizontal top wall, a vertical front flange and a stop adapted to engage the rear margin of said beam, and longitudinal ribs extending downwardly from the under surface of said top wall, said front wall having sliding engagement with said feed plate and said ribs bearing upon and having sliding engagement with said beam, a shaft extending longitudinally of the section between said ribs, and a block having screw-threaded engagement with said shaft and adapted for engagement with said beam during the forward stroke of the latter.

9. In a furnace, the combination with a feed hopper and a feed plate, of a reciprocating beam, having an upwardly facing surface, a plurality of pusher sections having sliding connection therewith, each of said sections comprising a horizontal top wall, a depending flange at its forward end adapted to bear upon said feed plate and to have sliding engagement therewith, ribs having downwardly facing bearing surfaces depending from said top wall, adapted to engage said beam, a depending flange on the rear end of said top wall, adapted to engage the said beam during the rearward motion of the beam, a screw shaft ex-

tending through the rearward flange and having bearing in the forward flange, and an adjustable stop mounted on said shaft and adapted to engage the front margin 5 of said beam during the forward movement of the latter.

10. In a furnace, the combination with a feed plate, of a reciprocating beam, a plurality of pusher sections mounted in laterally abutting relation along said beam, each of said sections embracing a horizontal top wall, forward and rear flanges and longitudinal ribs depending from said top wall and extending between said flanges, 15 said forward flange having sliding engagement with said feed plate, and said ribs having sliding engagement with said beam, a screw shaft extending longitudinally of each section between said ribs and having bearing at its ends in the front and rear flanges, and an adjustable stop mounted upon said shaft and adapted for contact 20 with said beam during the forward movement of the same to afford a variable degree of lost motion between the pusher section 25 and said beam.

11. In a furnace, the combination with a feed plate, of a reciprocating pusher beam, a plurality of pusher sections mounted side by side along said beam, each of said sections embracing a horizontal top wall, forward and rear flanges and longitudinal ribs extending between said flanges, said forward flange having sliding engagement with the feed plate, and said ribs having sliding engagement with said beam, a rotative shaft extending through said rear flange and having bearing in said forward flange, a non-rotatable stop mounted upon said 40 shaft and having screw-threaded engagement therewith, said stop being adapted to afford a variable degree of lost motion between the section and the beam during the forward movement of said beam.

45. 12. In a furnace, the combination with a feed plate, of a reciprocating beam, a plurality of pusher sections mounted in laterally abutting relation along said beam and bearing upon and in sliding engagement 50 with said feed plate at their forward mar-

gins, said sections comprising end sections rigidly secured to said beam and intermediate sections, said intermediate sections having sliding engagement with said beam and being provided with means affording 55 varying degrees of lost motion between said intermediate sections and said beam during the forward movement of the latter.

13. In a furnace, the combination with a feed plate, of a reciprocating beam located 60 adjacent to said feed plate, a plurality of pusher sections mounted in laterally abutting relation along said beam and bearing upon and in sliding engagement with said feed plate at their forward margins, the end 65 sections being rigidly secured to said beam and the intermediate sections being mounted in sliding engagement with said beam, driving means associated with said end sections, and means associated with each of 70 said intermediate sections adapted to afford a varying degree of lost motion between said sections and said beam during the forward movement of the beam.

14. In a furnace, the combination of a 75 feed hopper and a feed plate, of a reciprocating pusher beam, extending transversely of the furnace, and pusher sections secured to the ends of said beam, each of said sections being provided with a lug extending 80 outwardly and rearwardly therefrom, a rock shaft provided with two rocking arms, links pivotally connected with the lugs in said end sections and with said arms, and a plurality of intermediate pusher sections 85 disposed along said beam between said end pusher sections, each of said intermediate pusher sections being provided with means adapted to afford a variable degree of lost motion between the same and the reciprocating beam during the forward movement 90 of said beam.

In testimony, that I claim the foregoing as my invention I affix my signature in the presence of two witnesses, this 4th day of 95 March A. D. 1912.

JOSEPH HARRINGTON.
